UNITED STATES PATENT OFFICE.

RALPH A. MEGENITY, OF KANSAS CITY, MISSOURI

CONCRETE CONSTRUCTION.

1,402,429.

Specification of Letters Patent. Patented Jan. 3, 1922.

Application filed January 16, 1920. Serial No. 351,938.

To all whom it may concern:

Be it known that I, RALPH A. MEGENITY, a citizen of the United States, residing in Kansas City, in the county of Jackson, in the State of Missouri, have invented an Improvement in Concrete Constructions, of which the following is a specification.

The object of the present invention is to improve and simplify my former constructions which are illustrated and described in Letters Patent of the United States No. 1,280,516, dated October 1, 1918 and No. 1,285,768, dated November 26, 1918, respectively.

In the present drawing: Figure 1 is a perspective view of a wooden form for concrete to which a metal stud has been secured. Figure 2 is a similar view showing a different form of stud. Figure 3 is still another view similar to Figure 1 in which a section 10 of a cementitious body is shown in relation to a stud. Figure 4 is a vertical section of a finished wall with a facing secured thereto in accordance with the invention. Figure 5 is a detailed view of a hook which may be 15 used as a tie-piece in carrying out my invention. Figure 6 a transverse sectional view of the stud shown in Figure 2.

The metal stud employed in the present case consists of a piece of wire which is 20 bent to form anchoring means 10 which become embedded in the concrete after the same has been poured, and faces or attachment portions 15 which lie exposed along the surface of the concrete after the same has 25 hardened and the wooden forms have been removed. In Figures 1 and 2, there are illustrated two different forms into which a wire may be bent to serve the purpose of the present invention, that is, to provide anchoring means and faces in a stud of the present 30 type; and it will be obvious that a number of other possible forms exist in which wire 35 may be bent for this purpose.

In carrying out my invention the bent 40 wire is first secured to the wooden forms, as for instance by means of staples 12. The studs when so secured to the forms are maintained in fixed position due to the fact that the attachment portions 15 are laterally 45 spaced and therefore prevent rotation of the studs. It will be obvious at once that this 50 operation is very simple and can be accomplished readily and quickly by workmen.

After the cement has been poured and the 55 wooden forms removed, a tool is inserted behind the exposed faces of the stud so as to make an opening into which the tie-pieces

11 may be hooked. It is immaterial, so far as the present invention is concerned, whether these openings be made by gouging 60 out part of the concrete behind the exposed faces of the stud or whether the exposed faces are drawn out by the tool to a sufficient extent to permit the introduction of the tie-pieces between the surface of the wall 65 or other body and the drawn-out faces of the studs.

After the tie-pieces have been inserted, the facing is attached thereto in a manner varying of course in accordance with the 70 particular facing which is employed. In the present case, where the facing consists of blocks 2 and mortar 3, the application of said blocks and mortar require no detailed explanation.

The invention may be applied to any 75 cementitious body, including ceilings and floors as well as walls and other concrete constructions.

I claim as my invention:

1. A stud of the character described consisting of a wire bent to form attachment portions lying in one plane, adjacent attachment portion being laterally spaced from each other to prevent rotation of the 85 stud as a whole and anchor portions connecting the attachment portions and projecting laterally from the plane of the attachment portions.

2. A stud of the character described consisting of a wire bent to form attachment portions lying in one plane, adjacent attachment portion being laterally spaced from each other in parallel lines and anchor 95 portions connecting the attachment portions projecting substantially at a right angle in one direction from the plane of the attachment portions.

3. A stud of the character described consisting of a wire bent to form attachment 100 portions lying in one plane adjacent attachment portion being laterally spaced from each other in parallel lines and anchor portions connecting the attachment portions projecting substantially at a right angle in 105 one direction from the plane of the attachment portions, each anchor portion consisting of a U-shaped bend the ends of which are connected to adjacent ends of attachment portions.

In testimony whereof, I have signed my name to this specification this 3rd day of January, 1920.

RALPH A. MEGENITY.
